ACCESSORY FOR CEMETERIES

Application filed May 20, 1930. Serial No. 454,166.

This invention relates to an accessory for cemeteries or burial plots, and comprehends an accessory which serves in the capacities of a combined kneeling step and storage compartment for garden tools or other requisites essential to maintain a burial plot or grave in proper condition.

The invention further aims to provide an accessory of this character which, in addition to its utilitarian purpose, is constructed in such a manner as not to detract from the general appearance of the grave or plot, but which rather serves to further enhance its appearance or increase the general esthetic effect.

The invention furthermore embodies, in an accessory of the indicated character, means for effectually anchoring the same in place against theft or accidental displacement.

Other objects of the invention reside in the simplicity of construction of the accessory, the economy with which it may be produced and emplaced and the general efficiency derived therefrom.

With the above recited and other objects in view, reference is had to the following description and accompanying drawings, in which there is exhibited one example or embodiment of the invention, while the claims define the actual scope of the same.

In the drawings:

Figure 1 is a perspective view illustrating the manner in which the accessories are associated with a grave or burial plot.

Figure 2 is an enlarged longitudinal sectional view through the accessory in its applied position, and illustrating the manner in which the same is devised for the accommodation of garden tools or other implements.

Figure 3 is a fragmentary longitudinal sectional view through one of the accessories, showing the same housing a water sprinkler container.

Figure 4 is a transverse sectional view taken approximately on the line 4-4 of Figure 2.

Figure 5 is a perspective view of the garden tool or implement container removed.

Referring to the drawings by characters 50 of reference, the invention comprehends pref-

erably the employment of a pair of the accessories for each grave, although, obviously, one of the same may be used. In the present illustration, a pair of accessories is disclosed, designated generally by the reference characters A and B. Each of the accessories A and B consists of a combined kneeling step and storage member, which is preferably formed from sheet metal bent or otherwise constructed to provide an upper wall 10 and depending side walls 11, each of which is formed with inturned flanges 12 at its lower end.

In order to provide means for anchoring the same in place, one or more cross bars or straps 13 are employed, which are secured to the under side of the flanges 12 in any desired manner, such as by spot welding, riveting or the like. The cross straps 13 are of a length to extend slightly beyond the depending side walls 11, and the opposite ends are

provided with downwardly extending extremities or legs 14 and outturned apertured terminals or feet 15 at the lower ends of the extremities or legs 14. In practice, the accessory as used in the example illustrated will have the opposite ends open, and what will be termed the rear ends 16 thereof will be closed by abutting the same against the base C of the headstone D. Also in the example illustrated, the accessory A will receive a container 17, in the nature of a drawer, which is provided with a bottom wall 18, side walls 19 and front and rear end walls 20 and 21, the top being open. The container or drawer 17 is of a cross sectional size or

area to fit within the step or housing, which forms a receiving compartment therefor, so that the same may be slid longitudinally on the flanges 12. The front end wall 20 of the container or drawer 17 will be provided with a centrally disposed, forwardly projecting, preferably U-shaped, handle 22, which also serves in the capacity of a staple which is

designed to project through a slot 23 in a hasp bar 24 hingedly connected by a hinge pin 25 to a leaf 26 suitably secured upon the upper wall 10 at the forward end of the accessory A. A padlock 27 may be engaged with the handle or staple element 22 for the purpose of locking the container or drawer

within the receiving compartment defined by the step or housing.

The opposite accessory B, where the same is used in pairs as illustrated, may constitute 5 a receiving compartment or housing for a water sprinkling receptacle 28, which will preferably be shaped to fit and slide within the accessory B, similar to the manner in which the container or drawer 17 fits into 10 the accessory A. The water sprinkler container 28 will be provided with a sprinkler head 29 constituting a removable cap for the nozzle 30, through which the water may be introduced to the receptacle 28, and a handle 15 31 may be formed at the nozzle end of the receptacle 28. The outer end 32 of the receptacle 28 will always be provided with a U-shaped centrally disposed handle 22, which 20 also constitutes a staple and which functions in connection with the hasp bar 24, as previously explained.

The accessories A and B are emplaced by sinking the extremities 14 and legs 15 in the ground, with the lower flanged ends 12 approximately flush with the ground, after 25 which spikes 33 are driven through the apertured terminals or feet 15. It is, of course, understood that the extremities or legs 14 and feet 15 are subsequently covered to conceal 30 the same from view and at the same time to further act to anchor and conceal the legs, feet and spikes from view. It is to be understood that within the scope of the invention, 35 where a grave or burial plot is not provided with a headstone, the rear end 16 may be otherwise closed, and, if desired, where only one of the accessories A or B is used, the container or drawer 17 may be arranged within 40 in one end and the water sprinkler container at both ends.

While there has been illustrated and described a preferred embodiment of the invention by way of example, it is to be clearly 45 understood that no restriction is intended to the precise structural details and that variations and modifications of the invention, which properly fall within the scope of the appended claims, may be resorted to when 50 desired.

What is claimed is:

1. In an accessory for cemeteries, an elongated hollow member adapted to be arranged alongside of a grave to constitute a kneeling 55 step and defining therein, a storage compartment for tools and other requisites for maintaining the grave in proper condition and means for anchoring the same to the ground consisting of a cross bar secured to the under 60 side of said member, said cross bar having depending opposite ends and right angularly disposed apertured terminals sunk into the ground and anchoring spikes driven through said apertured terminals further into the 65 ground.

2. In an accessory for cemeteries, an elongated hollow member adapted to be arranged alongside of a grave to constitute a kneeling step and defining therein, a storage compartment for tools and other requisites for maintaining the grave in proper condition and means for anchoring the same to the ground consisting of a cross bar secured to the under side of said member, said cross bar having 70 depending opposite ends and outturned apertured terminals sunk into the ground and anchoring spikes driven through said apertured terminals further into the ground. 75

3. In an accessory for cemeteries, an elongated hollow member adapted to be arranged alongside of a grave to constitute a kneeling step and defining therein, a storage compartment for tools and other requisites for maintaining the grave in proper condition and means for anchoring the same to the ground 80 consisting of a cross bar secured to the under side of said member, said cross bar having depending opposite ends and offset apertured terminals sunk into the ground and anchoring spikes driven through said apertured terminals further into the ground. 85

4. In an accessory for cemeteries, an elongated hollow member adapted to be arranged alongside of a grave to constitute a kneeling step and defining therein, a storage compartment for tools and other requisites for maintaining the grave in proper condition, said member being fashioned from sheet material to provide an upper wall, depending side 90 walls and inturned flanges at the lower ends of said side walls and a receptacle slidably arranged within said member for introduction and removal through one end thereof. 95

5. In an accessory for cemeteries, an elongated hollow member adapted to be arranged alongside of a grave to constitute a kneeling step and defining therein, a storage compartment for tools and other requisites for maintaining the grave in proper condition, said member being fashioned from sheet material to provide an upper wall, depending side 100 walls and inturned flanges at the lower ends of said side walls and a receptacle slidably arranged within said member for introduction and removal through one end thereof, 105 said receptacle and member provided respectively with interengageable means at one end for locking the receptacle against removal from the member. 110

6. In an accessory for cemeteries, an elongated hollow member adapted to be arranged alongside of a grave to constitute a kneeling step and defining therein, a storage compartment for tools and other requisites for maintaining the grave in proper condition, said member being fashioned from sheet material to provide an upper wall, depending side 120 walls and inturned flanges at the lower ends of said side walls, a receptacle slidably arranged within said member for introduction 125 of said side walls, a receptacle slidably arranged within said member for introduction 130

and removal through one end thereof, said receptacle and member provided respectively with interengageable means at one end for locking the receptacle against removal from

5 the member and means on said receptacle also serving as a handle for sliding the same into and out of the member.

7. In an accessory for cemeteries, an elongated hollow member adapted to be arranged
10 alongside of a grave to constitute a kneeling step and defining therein, a storage compartment for tools and other requisites for maintaining the grave in proper condition, said member being fashioned from sheet material
15 to provide an upper wall, depending side walls and inturned flanges at the lower ends of said side walls, a receptacle slidably arranged within said member for introduction and removal through one end thereof, said
20 receptacle and member provided respectively with interengageable means at one end for locking the receptacle against removal from the member, means on said receptacle also serving as a handle for sliding the same into
25 and out of the member and means at the end of said member in the form of a hasp, adapted to receive through its slotted portion the handle of said receptacle.
